UNITED STATES PATENT OFFICE

2,556,671

COMBINATION WET AND DRY HEAT GENERATOR

George Auslander, Long Island City, N. Y.

Application March 30, 1948, Serial No. 17,820

1 Claim. (Cl. 237—16)

1

The present invention relates to a heat generating unit, particularly adapted for household heating, although capable of more general use, the primary object of the invention being to provide a self-contained unit of simple construction and high efficiency adapted to provide both wet heat and dry heat simultaneously to areas where such a split system is more advantageous than use of a single system. Thus bathrooms and kitchens may be heated by a closed circuit through either steam or hot water heat, and the rest of the house heated by means of an open circuit, to wit, warm air. A submerged heating coil furnishes water for domestic purposes. The unit may be fired with either oil, gas or coal.

The invention will be described with reference to the accompanying drawings, in which:

Figure 1 is a sectional isometric view taken longitudinally through an embodiment of the invention and on line 1—1, Fig. 2;

Figure 1a is a longitudinal vertical section through a modified form of the device;

Figure 2 is a front end elevation of the structure shown in Fig. 1;

Figure 3 is a vertical section on the line 3—3 of Fig. 1.

Referring to Figures 1, 2 and 3 of the drawings, I have therein shown a unit comprising a continuous sheet bent into formation to provide side walls 1 connected by an arcuate top area and to which a front plate 2 and a rear plate 3 are welded. The said unit is mounted on a rectangular base 4 which constitutes a fire box and to which access is given by an opening at 5.

A series of marginally flanged inverted box-like members 6, 7 and 8 are welded together at their base flanges and to the side and front walls 1 and 2. Members 6 and 7 are flue-connected by a short tube 9 and member 8 is flue-connected by a short tube 10 with the rear wall 3. This arrangement provides three chambers for the hot gases generated in the fire box, which chambers are preferably closed at their sides and tops, each by an arcuate plate as indicated in Fig. 3, such plate being entirely surrounded by boiler water, as indicated by the horizontal space lines in Figs. 1a and 3. The flue pipe 10 will lead to a stack, as customary, for carrying off waste gases or smoke from the combustion within the fire box.

In the forms shown in Figs. 1, 2 and 3, the upper areas of front and rear plates 2 and 3 support between them a series of horizontal tubes 11 which tubes will be surrounded by steam or hot water in accordance with the type of "wet heat" circulation. The tubes may be internally baffled, if desired, as indicated at 11x, Fig. 1.

2

At the front of the structure is welded or otherwise secured a fan box 12, provided with an air filter or screen at 13, and having an intake duct 14 which may be employed as a manifold for communication with branch ducts (not shown) leading from a plurality of floor areas in rooms to be heated with "dry heat." A motor driven fan 15 is mounted in the box 12 with its blades acting to force air through the tubes 11.

10 At the rear of the structure is a hot air outlet chamber 16 communicating with a duct 17, and the latter may serve as a manifold for communication with branch ducts (not shown) leading to room areas to be heated by hot air.

15 At the top of the arcuate plate 1 (see Fig. 1) is an outlet 18 at which a steam or hot water pipe may be connected and which will lead, by suitable branches, to radiators. A safety blow-off valve is schematically indicated at 19.

20 A household-supply hot-water generating tube, which may be U-shaped, is placed in the water chamber of the structure, as shown at 19, Fig. 1.

An inlet for feed water for the boiler is indicated at 20, and a draw-off outlet is indicated at 25 21. Of course these may be reversed, as to position of use.

In the operation of the heat generator, combustion gases generated primarily in the fire box 6 and circulated through the chambers 7 and 8 will raise the temperature of water in the boiler to that desired either for steam or hot water heating, and at the same time will heat water circulated through hot water generator 19 for household use, the steam or hot water passing to radiators as customary.

35 The radiators may be located in rooms where withdrawal of cool air and its recirculation is not desirable, as in kitchens, bath rooms or laundries. For many uses the "wet heat" thus employed, may be considered as the secondary output of the generator, and "dry heat" its primary function.

When the boiler is thus put into action, fan 15 customarily thermostatically controlled from rooms calling for heat, will be thrown into action and cool air withdrawn from the rooms (as explained above) will be forced through the tubes and heated by conduction from their hot walls, aided by baffles 11x in the tubes, when such baffles are used. The hot air will be received by chamber 16 and will pass through duct 17 (and room ducts when used) to room hot air outlets.

In the modification shown in Fig. 1a the boiler construction is the same as shown in the preceding figure and in Figs. 2 and 3, but the air heating elements are changed in that the tubes 55 11 are substituted for a large cylinder 22 which

is internally baffled, preferably by a continuous metal strip spirally turned and welded to the inner wall of the cylinder. Such a continuous spiral strip when cut longitudinally, will be in sections generally of the form shown at 23, Fig. 1a. In that figure a branch cool air intake pipe is shown at 24, and branch hot air pipes or ducts are shown at 25. This form of air heat generator is of lower cost and more readily constructed than the form of Figs. 1, 2 and 3.

Having described my invention, what I desire to secure by Letters Patent, is as follows:

A combination wet and dry heat generator comprising an integral arcuate plate forming the side walls and top of a combined fire-box and combustion chamber, a water chamber within and laterally bounded by said arcuate plate, front and rear closure plates secured to the arcuate plate, hollow members having base flanges along their lower portions, said base flanges being connected to each other and to the front and rear closure walls, said hollow members forming a bottom for said water chamber and providing relatively narrow spaced water-filled baffles projecting into the fire-box and combustion chamber and extending from side to side of the arcuate plate, the upper areas of the front and rear closure wall plates having a pair of horizontally-aligned apertures, a duct extending through said apertures and the water chamber and in heat transfer relationship with the latter, baffle means

5 within said duct for directing air flowing therethrough into efficient heat transfer contact with the walls of the duct, a horizontal air inlet conduit at one end of the duct in communication therewith, a horizontal air discharge conduit at the other end of the duct and in communication therewith, said duct and conduits being in axial alignment, fan means for forcing air to be heated from said air inlet conduit through said duct to said air discharge conduit, and out-flow and in-flow means communicating with said water chamber whereby hot water or steam may be withdrawn therefrom and then returned thereto after being circulated in the form of "wet heat."

10 15 GEORGE AUSLANDER.
